US00D737822S

(12) **United States Design Patent**
Mistkawi et al.

(10) **Patent No.:** US D737,822 S
(45) **Date of Patent:** ** Sep. 1, 2015

(54) **OPTICAL MODULE**

(71) Applicant: **Datalogic IP Tech S.r.l.**, Lippo di Calderara di Reno (IT)

(72) Inventors: **Joseph G. Mistkawi**, Tigard, OR (US); **Federico Canini**, Zola Predosa (IT); **Anna Guagliumi**, Calderara di Reno (IT)

(73) Assignee: **DATALOGIC IP TECH S.R.L.**, Lippo di Calderara di Reno (IT)

(**) Term: **14 Years**

(21) Appl. No.: **29/501,824**

(22) Filed: **Sep. 9, 2014**

(30) **Foreign Application Priority Data**

Mar. 10, 2014 (EM) 002421560

(51) **LOC (10) Cl.** **14-02**

(52) **U.S. Cl.**

USPC **D14/420**; D14/453

(58) **Field of Classification Search**

USPC D14/421-425, 420; D18/55, 49, 46, 40, D18/36-39, 41, 44, 45, 47, 48, 50-54, 56; 235/462, 455, 470, 462.43, 482, 483, 235/462.21, 472.01, 435, 439, 440, 446, 235/454, 461, 462.32, 462.35, 462.41, 235/462.42, 463; 358/474, 486, 488, 496, 358/497, 498, 452, 449, 451, 453, 1.13; 318/685, 696; 355/81, 75; 399/405, 399/367, 379, 380; 382/217; 715/209, 222, 715/226, 274; 400/613, 613.1-613.4, 400/690.1-690.4, 691-694

CLAIM

We claim the ornamental design for an optical module, as shown and described.

DESCRIPTION

FIG. 1 is a perspective front view of an optical module according to the present invention.

FIG. 2 is a front elevation view of the optical module of FIG. 1.

FIG. 3 is a rear elevation view of the optical module of FIG. 1.

FIG. 4 is a top view of the optical module of FIG. 1.

FIG. 5 is a bottom view of the optical module of FIG. 1.

FIG. 6 is a left side elevation view of the optical module of FIG. 1; and,

FIG. 7 is a right side elevation view of the optical module of FIG. 1.

Broken lines and unshaded portions contained within broken lines are not claimed.
